UNITED STATES PATENT OFFICE.

JOHN E. WOOLVERTON, OF CINCINNATI, OHIO, ASSIGNOR OF TWO-THIRDS
TO ORRIN CADY AND GEORGE W. SMITH, BOTH OF SAME PLACE.

DEVICE FOR DISPLAYING ADVERTISEMENTS.

SPECIFICATION forming part of Letters Patent No. 392,939, dated November 13, 1888.

Application filed May 28, 1888. Serial No. 275,292. (No model.)

To all whom it may concern:

Be it known that I, JOHN E. WOOLVERTON, a citizen of the United States, residing at Cincinnati, Hamilton county, State of Ohio, have 5 invented a new and useful Device for Displaying Advertisements, of which the following is a specification.

My invention consists, chiefly, in a clock the mechanism of which releases at intervals other 10 independent mechanisms in such a manner as to display successively and alternately a number of advertisements connected therewith.

The object of my invention is to display advertisements as conspicuously as possible by 15 connecting them with a clock, which, when exposed in a prominent location, naturally attracts the attention of the public to a high degree and insures to the advertiser an extensive publication of his business.

20 In the drawings, Figure 1 is a front view of the clock, showing one central and two lateral advertising-spaces. Fig. 2 shows in a front view the inside of the case and the arrangement and location of the mechanisms. Figs. 25 3 and 4 show in a front and side view, respectively, the mechanism operating the advertisements in the lateral advertising-spaces, the front part of the frame being removed in Fig. 3. Fig. 5 is a partial rear view of the same, 30 showing parts of the rock-shaft. Fig. 6 is a front view of the mechanism operating the advertisements in the central space, the front part of the frame being removed. Fig. 7 is a side view of the same. Fig. 8 is an end view 35 of roller 20 and part of the case in section. Fig. 9 shows one of the leaves in the central space and its rod detached. Figs. 10, 11, 12, and 13 are diagrammatic side views of the tumbling frames, showing them in different 40 positions while tumbling.

12 is the clock-case, of suitable shape and more or less ornamental.

13 is the dial, and 14 the mechanism operating the hands thereon. 45 15 15 are two lateral and 16 is a central opening in the front of the case, closed by glass, behind which the advertisements are displayed. Those in the lateral spaces are fastened to a series of wire panels, A B C, each series connected to rock-shafts 18, 18, operated by a mech-

anism, 19, whereby the panels are alternately tilted front and rearwardly. The special construction of these panels will be more fully explained hereinafter. The advertisements in the central space are secured to a roller, 20, 55 which is turned by means of a pair of beveled wheels, 21, shaft 22, and a mechanism, 23.

The clock-movement 14, which may be of any well-known construction, and the other two movements, 19 and 23, may be driven by 60 either springs or weights. In the present case weights have been preferred for the movements 19 and 23. The construction of the movements, in the main, is very simple and does not differ very much from any ordinary 65 clock-movement. Many modifications are possible, and the arrangement of the different trains of wheels depends a good deal on the length of time they are desired to run.

The following description illustrates the construction of the two movements 19 and 23 as far as they are alike:

24 are ropes or chains passing over guide-pulleys 25, carrying on one end the necessary weights and fastened with their other ends to 70 drums 26. The weights are not shown here, and are supposed to be outside of the clock-case.

27 are gear-wheels fast with drums 26, and transfer the power of the weights over to a pinion, 28. From here, by means of another gear-wheel, 29, on same shaft with pinion 28, another transfer takes place to pinion 30 on shaft 31. On this same shaft is a gear-wheel, 32, engaging into a pinion, 33, on shaft 34. 85 On the end of this shaft is an arm, 35, engaging with the pins of an escape-wheel, 36, of the clock-movement 14.

The weights of the mechanisms 19 and 23 tend to move them and all parts connected 90 with them continuously as long as they are wound up, and would do so if escape-wheel 36, engaging arms 35, did not arrest their continuous run. Escape-wheel 36 is moved by the clock-movement, and its speed is slower than 95 the speed of the arms 35 on shaft 34. Every time the pins in escape-wheel 36 clear the arms 35 movements 19 and 23 are at liberty to move, and keep on going until arm 35 is arrested again by the next pin in wheel 36, which 100

has meanwhile advanced into the path of the former's rotation. During the time the two movements are going a change of the advertisements takes place. Rock-shafts 18 18 are 5 tilted a half-revolution, or one hundred and eighty degrees, and roller 20 is turned far enough to drop another leaf and lift the next one sufficiently to be ready to drop next.

The special construction used for tilting the 10 rock-shaft is as follows, reference being had mainly to Figs. 2, 3, 4, and 5: On each end of arbor 31 is a crank, 56, which is connected by a connecting-rod, 57, to a rack, 58, properly guided and engaging with cog-wheels 59 15 on shafts 18. A movement of the rack in either direction turns shaft 18 just one-half revolution. The special construction for turning the roller 20 is as follows, reference being had to Figs. 2, 6, and 7: On the end of shaft 20 31 sits a bevel-wheel, 37, engaging in another wheel, 38, on upright shaft 22. Another pair of bevel-wheels, 21—one on shaft 22 and one on the shaft of roller 20—completes the connection. Roller 20 has two flanges, 39 39, which 25 are perforated for the reception of rods 40, on which the advertisements 41 are hung. These rods 40 are extended out some distance from the flange 39 on one side, so as to strike the heel 42 of a bell-hammer, 43, thereby sounding a bell, 44, at every partial revolution and calling the attention of the observer to the change of advertisements taking place at this moment.

45 is a spring fastened to the back of the 35 case, pressing against the sheets on rods 40, and is intended to prevent the dropping of more than one sheet at a time.

The advertisements in the lateral spaces are fastened to the two sides of a series of frames 40 or panels, A B C D, (see Fig. 2,) of which the uppermost frame of each series is connected to a rock-shaft, 18. The frames are connected by links *d d*, *e e*, *f f*, *g g*, *h h* in such manner that the top bar of one frame is connected to 45 the top bar of the next lower frame by links *d d*, *f f*, *h h*, and the lower bar of one frame is connected to the lower bar of the next frame below by links *e e*, *g g*, and so on. The further action of the rock-shaft is as follows, 50 the description of one answering for both: Rock-shaft 18 turns, as shown by the direction of the arrow, (see Fig. 10,) and the uppermost frame, being fastened thereto, is turned with it and lifts frame B and all the 55 other frames hanging below. When the rock-shaft has almost completed its half-turn and frame A is in about a position as shown in Fig. 11, frame B tumbles, (see Fig. 12,) and when it reaches a vertical position frame C tumbles, (see 60 Fig. 13,) and when the latter has tumbled the next one drops, and so on all the way down. The effect of this tumbling is the changing of the bottom bars, 2, 4, 6, to be top bars, (see Figs. 2 to 13,) and the exposure on the frames 65 of the rear part of the panels with the advertisements. The letters of the advertisements on one side of a panel must be in an inverted

position relatively to the letters of the advertisement on the other side. The mechanism actuating the rock-shaft is supposed to stop 70 now for a certain time, its arm being arrested by the escape-wheel. After the release of arm 35 the mechanism begins to work again, the rock-shaft turns back and turns frame A in the direction of the arrow, (see Fig. 13,) 75 the frames are lifted and tumble again, as described before, only in an opposite direction, and the other side of the panels with their advertisements are exposed again.

From the foregoing description it is plain 80 that in the lateral spaces two different advertisements are alternately exposed on one panel, whereas in the middle roll any convenient number—say 12 to 20—are exposed successively before they commence to repeat again. 85 In the construction shown the advertisements in the middle space and the ones in the side panels change simultaneously, if desired, however they may change independently. This effect is easily accomplished by having two 90 different escape-wheels for each mechanism, or two sets of pins on the one wheel. The length of exposure is dependent on the spaces between the pins of the escape-wheel, and may be regulated accordingly. It may also be regulated by having more arms 35 on the respective arbors, or a star-shaped wheel. 95

I claim—

1. In a device for displaying advertisements, the combination of a clock-case having a dial 100 and suitable openings to display advertisements, a revolving roller adapted to receive a number of advertising-sheets, and a series of tumbling frames, A B C D, having advertisements secured to them, as explained. 105

2. In a device for displaying advertisements, the combination of a clock mechanism, a mechanism to operate a rock-shaft, tumbling frames adapted to receive and exhibit cards connected thereto, and an escapement interposed between the two mechanisms, for the purpose explained. 110

3. In combination with a suitable motive mechanism, a rock-shaft and a series of tumbling frames adapted to receive and exhibit 115 cards connected to the latter, as explained.

4. In a device for displaying advertisements, the combination, in a case, of a rock-shaft, a series of tumbling frames adapted to receive advertisements connected thereto, and a roller 120 intended for the same purpose, as explained.

5. In a device for displaying advertisements, the combination of a clock-case having a dial and suitable openings to display advertisements, a clock mechanism, a revolving roller 125 adapted to receive advertisements, a mechanism and suitable connection between the two to operate the roller, a rock-shaft, a series of tumbling wire frames adapted to receive and exhibit cards connected thereto, a mechanism to operate the rock-shaft, an escapement interposed between the clock mechanism and the other two mechanisms to regulate their motion, a spring, 45, behind roller 20, and an 130

alarm-bell operated by the latter, as and for the purpose explained.

6. In a device for displaying advertisements, the combination, in a case, of a clock mechanism, 14, mechanisms 19 and 23, located adjacent to the former, an escapement interposed between the clock mechanism and the two latter, a rock-shaft, 18, receiving an intermittent reciprocating rotary motion from mechanism 19, a series of tumbling wire frames, A B C D, suspended from said rock-shaft and adapted to receive and exhibit advertisements, and a roller, 20, operated by mechanism 23, as shown and described.

7. The tumbling wire frames, consisting of 15 a number of rectangular frames adapted to receive and exhibit advertisements, being closely connected with each other by links passing from top to top and bottom to bottom cross-bar of each frame, as shown, and for the 20 purpose described.

In testimony of which invention I hereunto set my hand.

JOHN E. WOOLVERTON.
